ILLUMINABLE ADVERTISING SIGN

Richard H. Van Den Berg, Milwaukee, Wis., assignor to Dimentional Products, Inc., Milwaukee, Wis., a corporation of Wisconsin

Filed Feb. 5, 1960, Ser. No. 59,282

Term of patent 14 years

(Cl. D1—12)

FIG. 6

Fig. 1 is a front elevational view of an illuminable advertising sign showing my new design;

Fig. 2 is a side elevational view, the opposite side being a substantial mirror image thereof;

Fig. 3 is a top plan view thereof;

Fig. 4 is a bottom plan view thereof;

Fig. 5 is a cross-section taken substantially on the line 5—5 of Fig. 1, and

Fig. 6 is an enlarged rear elevational view thereof.

I claim:

The ornamental design for an illuminable advertising sign, as shown.
